DESIGN FOR A BRACELET CHAIN

Eugen Prestinari, Summit, N. J., assignor to Gemex Company, Newark, N. J., a corporation of New Jersey

Application March 24, 1937, Serial No. 68,366

Term of patent 7 years

To all whom it may concern:

Be it known that I, Eugen Prestinari, a citizen of the United States and a resident of Summit, in the county of Union, State of New Jersey, have invented a new, original, and ornamental Design for a Bracelet Chain, of which the following is a specification, reference being had to the accompanying drawing, forming a part thereof,

In the drawing,

Figure 1 is a plan view of a section of bracelet chain showing my new design; and,

Figure 2 is a side elevational view of the chain shown in Figure 1.

I claim:

The ornamental design for a bracelet chain as shown.

EUGEN PRESTINARI,
